UNITED STATES PATENT OFFICE.

JOSEPH E. SAUMWEBER, OF LIDGERWOOD, NORTH DAKOTA.

TOOL.

1,280,555.

Specification of Letters Patent.

Patented Oct. 1, 1918.

Application filed May 22, 1917. Serial No. 170,266.

To all whom it may concern:

Be it known that I, JOSEPH E. SAUMWEBER, a citizen of the United States, residing at Lidgerwood, in the county of Richland and State of North Dakota, have invented new and useful Improvements in Tools, of which the following is a specification.

The present invention relates to improvements in tools of that class primarily adapted for extracting cotter pins or keys, and resides in the construction, combination and arrangement of parts set forth in the following description and falling within the scope 15 of the appended claim.

In the drawing:

Figure 1 is a perspective view of a tool constructed in accordance with the present invention,

20 Fig. 2 is a top plan view of the same, Fig. 3 is a sectional view approximately on the line 3—3 of Fig. 1, and

Fig. 4 is a sectional view approximately on the line 4—4 of Fig. 1.

25 Fig. 5 is a sectional view approximately on the line 5—5 of Fig. 1.

In the present construction of such tools employed for extracting cotter pins or keys which have come under my observation, 30 from experience, I have found that the same are not properly constructed to permit of the free operation thereof, especially in extracting or removing the keys employed in connection with castellated nuts, which class 35 of nuts are now commonly employed in connection with automobile constructions and other machinery work.

It may be therefore considered the primary object of the present invention to construct a tool of this character wherein the eye portion of the cotter pin may be readily engaged even when wholly received in the slots upon the face of a castellated nut and also whereby the tool is readily fulcrumed 45 upon the nut to permit of the free extraction of the key when the same is so positioned that only a small space is required in which to manipulate the tool.

The device, as illustrated by the drawings, 50 comprises two pivoted levers 1 and 2, respectively, the pivot being preferably in the nature of a headed stud 3 secured to one of the sides of the member 1 and having its shank received in an elongated slot 4 in the 55 other lever 2. The lever 2, beyond the pivot 3 comprises what I term a jaw 5, and the

said jaw may be formed upon its inner face with a knife extension 6 and the outer end of the said jaw is arranged angularly or at a curvature with respect to the longitudinal 60 plane of the lever 2 and terminates in a beak 7. This beak has its outer end, of course, terminating in a point and is rounded to its connection with the jaw proper.

The portion of the lever 1, beyond the 65 pivot 3, also provides what I will term a jaw and which is indicated by the numeral 8, the said jaw having its inner face straight and, when the jaw 5 is provided with the knife, formed with a slot 9 to receive the knife 70 member 6 of the jaw 5. The straight inner face at the outer portion thereof is stepped, as at 10, and this stepped portion is gradually rounded or arranged angularly in the direction of the beak 7 of the jaw 5. The 75 portion 10 is flat or straight and is provided at its outer end with an opening 11 through which the pointed end of the beak 7 is adapted to pass. The outer face of the portion 10 is concaved from the end thereof, as indicated by the numeral 12, and is rounded, as at 13, to the lower edge of the jaw proper, the said concaved portion 12 providing the outer end of the jaw 8 with a knife point 14, and the concaved portion 12 provides one of the fulcrum elements of the tool, the rounded or convex portion 13 providing another fulcrum point, and the rounded outer surface of the beak 7 providing still another fulcrum point. The end of the lever 1 may 85 be and is preferably sharpened, as at 15, and this sharpened end when inserted between the limbs of a cotter key or pin provides for the ready separation or spreading of the said means, while the knife member 6 permits of the cutting of the limbs of the key or pin, when it is found that the pin or key is of a greater length than required.

90 From the foregoing when taken in connection with the drawings, it will be noted by those skilled in the art to which such invention appertains, that the beak being rounded outwardly and angularly from the jaw 5 and the portion beyond the jaw 8 defined by the portions 10, 14 and 12 which 95 provide what I will term a nose that is also rounded angularly away from the jaw and in the direction of the beak, terminating in the sharpened point 14, permits of the tool engaging with the cotter pins arranged 100 in a comparatively small space for the operation of the tool and that the tool may 110

receive a fulcrum bearing at almost any angle with respect to the beak and nose.

Having thus described the invention, what I claim is:

- 5 A tool for the purpose set forth comprising two pivotally connected levers formed each with a jaw outward of the pivotal connection between the levers, both of said jaws being arranged at an outward angle in the
10 same direction from the respective levers

on which they are formed, one of said jaws, at the end thereof being formed with a downturned beak, the angle end of the other jaw having an opening to receive the beak, and a pointed nose on one of the corners of 15 the said end of the referred to last mentioned jaw.

In testimony whereof I affix my signature.

JOSEPH E. SAUMWEBER.
